COMBINATION WIRE AND BAND CUTTER,
BENDER, AND PERFORATOR

Henry M. Yeager, Williamsville, N. Y.

Refiled for abandoned application Serial No.
671,507, May 17, 1933. This application January 25, 1936, Serial No. 60,869

8 Claims. (Cl. 153—2)

This invention relates to a multiple tool for use in cutting, bending and punching holes in strips of sheet metal, and also cutting, bending and screw threading metal rods or wire. This apparatus is more particularly intended for manual training of boys in the art of making different mechanical devices such as bridges, tractors, steam shovels and other mechanical toys, but the same is also capable of use by adults for manufacturing or making articles of this character for commercial use.

It is the object of this invention to produce a multiple tool of this character which is simple in construction and low in cost and which can be operated efficiently for producing a variety of articles of wire or sheet metal which require punching, bending or threading in order to adapt them for some particular use and to permit such work to be done accurately, easily and economically.

In the accompanying drawings:

Figure 1 is a side elevation of the multiple tool embodying my improvements, viewed from one side thereof.

Figure 2 is an end elevation thereof, viewed from one end.

Figure 3 is an end elevation of the apparatus viewed from the end opposite to that indicated in Fig. 2.

Figure 4 is a vertical longitudinal section, taken on line 4—4 Fig. 3.

Figure 5 is a vertical transverse section on line 5—5 Fig. 1.

Figure 6 is a horizontal section taken on line 35 6—6 Fig. 1.

Figure 7 is a perspective view of a rod or wire which is adapted to be held in place by means of this apparatus to permit of forming a screw thread thereon.

Figure 8 is a similar view of a rod or wire which has been bent into angular form by the use of this apparatus.

Figure 9 is a similar view of a strip of sheet metal which has been perforated in this apparatus.

Figure 10 is a similar view showing a strip of metal which has been perforated and also bent into angular form by the use of this invention.

In the following description similar characters of reference indicate like parts in the several figures of the drawings.

In its general organization this multiple tool or apparatus comprises a stationary stand, means for clamping a wire, rod or the like and holding the same in place while forming a screw thread

or other operations thereon, gaging means whereby a rod, wire, strip of metal or the like may be properly positioned with reference to the tool which operates upon the same, bending means whereby the wire, rod, strip of metal or the like, may be bent into angular form, cutting means for severing wire, rods, strips of metal or the like into the required lengths, and perforating means for producing holes in sheet metal strips or the like.

The stand includes two L-shaped members, one of which has a horizontal foot 20 and an upright leg 21, and the other having a horizontal foot 22 and an upright leg 23, said feet being adapted to be secured to a bench or other suitable support by various means, as for example bolts passing through holes 24 in these feet and the two legs being spaced apart from each other, and the upper end of the leg 23 being offset outwardly from the corresponding upper end of the leg 21, as shown at 25, so that the spacing between the upper parts of the legs is somewhat greater than that between the lower part thereof.

These two L-shaped members of the stand may be held in place relatively to each other by any suitable coupling means, but in the present case these coupling means include a spacing washer 26 interposed between the lower central parts of the legs 21 and 23 and a fastening bolt 27 passing through this spacing washer and the adjacent parts of the legs 21 and 23, as best shown in Figs. 4, 5 and 6.

At one of the corresponding upright edges of the stand legs a bracket is mounted which serves as a means for supporting a strip of metal or a wire rod while bending the same into angular form. This bracket in its preferred form comprises an inwardly projecting flange 28 which is arranged between the lower parts of the legs of the stand at the respective front edges thereof, an upright transverse plate 29, engaging with the corresponding upright edges at the respective ends of the legs, and a supporting table or anvil 30 forming the upper part of this bracket and having an upwardly facing surface for supporting either a flat strip of metal or a round wire or rod preparatory to bending the same into angular form.

This bracket is secured to the legs of the stand by means of rivets 31 passing transversely through the flange 28 of the bracket and the adjacent parts of the legs 21 and 23, as best shown in Figs. 1, 4 and 6. The upper surface of the table or anvil 30 has its opposite ends 32, 33 arranged horizontally in line, and intermediate of these hori-

zontal surfaces this table or anvil is provided with a recess or notch 34 which is of V-shaped form and has its sides preferably arranged at right angles to one another, as shown in Fig. 2. A 5 bending jaw 35 having a right angle V-shaped face 36 for cooperation with the notch 34 is arranged above the anvil 30 so that upon placing a sheet metal strip, similar to the strip 37 in Fig. 9, upon the table 34 and forcing the jaw 35 downwardly against this strip, the latter will be bent so that two parts 38, 39 will be arranged at right angles to each other, as shown by full lines in Fig. 10.

It will be noted that the anvil or table 30 projects outwardly from the frame, as shown in Figs. 1 and 4, and the bending jaw 35 projects outwardly from the lever 44 and frame and over the anvil, as shown in Figs. 1 and 4, and is also comparatively narrow and short from its V-shaped underside or face and its upper side, as shown in Figs. 1, 2 and 4. By thus projecting the anvil and bending jaw from the frame and making the latter thin or narrow horizontally and short vertically it is possible to produce relatively short bends in wire and strips of metal and thus render the bending part of this apparatus particularly well suited for use by boys in making parts for small models while engaged in manual training. For example, as shown by dotted lines in Fig. 2, the end 39 of a metal strip has been bent so as to form a square loop which completely surrounds the bending jaw 35 without interfering with the operation of making the three bends in the strip necessary to form this loop.

For the purpose of enabling this handle and the bending jaw 35 to be also utilized for bending wire rods into angular form the underside of the jaw 35 is provided with a transverse notch 40 which is adapted to receive the upper side of a 40 wire rod which is to be bent. Upon placing a straight wire rod, such as that shown at 41 in Fig. 7, upon the horizontal surfaces 32, 33 of the anvil 30 and moving the jaw 35 downwardly with the notch 40 thereof in engagement with the upper side of the wire rod, the latter will be bent between the cooperating V-shaped surfaces 36 and 34 of the bending jaw and anvil into the angular form shown in Fig. 8, in which the two parts 42, 43 of this rod are arranged at right angles to each other.

This bending jaw is arranged on one part of a rocking lever 44 which is arranged between the upper parts of the legs of the stand and is pivotally mounted thereon so as to turn in a vertical plane by means of a pivot bolt 45 passing through this rock lever and the adjacent parts of the stand legs 21, 23 as shown in Figs. 4 and 5.

A rocking motion is imparted to this lever by means of an eccentric or cam 46 which is arranged between the upper ends of the stand legs and engages one of its flat sides with the inner side of the leg 21 while its periphery engages with opposite sides 47 of a notch 48 formed in the upper part of the rocking lever. This eccentric or cam is rotated by means of a hand lever 49 which is arranged between the eccentric or cam 46 and the opposite upper part 25 of the other stand leg, and this cam or eccentric and the hand lever 45 are pivotally mounted on the stand by means of a pin 50 passing through the cam, hand lever and the upper parts of the stand legs, as best shown in Figs. 4 and 5.

Connection between the cam and the hand lever 49 may be effected in various ways, for ex-

ample by means of a pin 51 passing transversely through the same.

On that end of the apparatus opposite to that on which the bending anvil 30 and bending jaw 35 are located, the apparatus is provided with 5 means for cutting and perforating strips of sheet metal and the like. These last-mentioned means include an L-shaped bracket having an upright plate 52 secured to the outer side of the stand leg 21 by means of rivets 53 and a horizontal plate 10 54 extending from the upper end of the vertical plate 52 over the undersides 55, 56 of recesses 57, 58 formed in the upper parts of the vertical faces of the stand legs, and thereby serve as a table 15 for supporting sheet metal strips or the like 15 which are to be perforated. This table is provided with a die opening 59 which is adapted to receive a vertically movable punch or tool 60 for producing perforations 61 in the strips of metal, shown in Figs. 9 and 10, by placing these 20 strips or similar articles on the die table 54 and forcing the punch or tool 60 downwardly against this strip of metal and into the die opening 59. The material removed from the strip of metal at this time passes downwardly into the space 25 between the legs of the stand and then escapes downwardly therefrom, where it can be disposed of in any suitable manner.

This punch or perforating tool 60 is mounted on the underside of a rocking arm 62 on the adjacent part of the rock lever 44 opposite to the bending jaw 35, as best shown in Fig. 4, so that upon oscillating the hand lever 49 and the cam 46 a rocking motion will be imparted to the punch in unison with the bending jaw 35 which are 35 mounted on opposite sides of the rock lever 44.

For convenience in spacing the holes in a strip of metal which is to be perforated uniform distances apart, the die table 54 is provided on one side of the punch opening 59 with a gage opening 63 which is spaced from the punch opening 59 a distance equal to that which is desirable to space apart the openings in the strip of metal.

In using this punching device for producing a row of perforations which are spaced equal distances apart, the hole is first punched in the strip by means of the punch 60 and die opening 59 and then this strip is advanced so that the opening just formed therein is in line with the gage opening 63, after which a pin is inserted through 50 this first opening of the strip and the gage opening 63, and thereby hold the strip in the properly spaced position for forming the next opening in the strip. This gaging operation is repeated for each additional opening of the row which is to 55 be formed in the strip and thereby enables successive openings to be properly spaced and permits of producing an accurate product in which the strip forms a part.

For the purpose of permitting the strip of 60 metal to be gaged laterally so that the perforations which are formed therein are arranged at the desired distance from one of the longitudinal edges of the strip, a gage may be employed similar to that which is shown in Figs. 1, 2, 3 and 5, which 65 preferably consists of a horizontal longitudinally slidable plate 64 which is provided with a longitudinal slot 65 receiving the pivot bolt 45 and adapted to be clamped between the nut 66 of this bolt and the outer side of the stand leg 21, and 70 provided at one end with a gage lug 67 extending across the gap formed by the notch 57, and also provided with a finger piece 68 for shifting this gage plate.

By adjusting the plate 64 so that its gage lug 67 75

is in the desired position lengthwise of the gap 57 it is then possible to place the strip to be perforated against this gage while producing perforations therein and insure locating these perforations at the proper distance from the longitudinal edges thereof.

For the purpose of cutting wires by means of this tool the arm 62 of the rock lever 54 is provided with an opening 69 which is adapted to 10 operate with an opening 70 in the stand leg 21, so that these parts form the blades of a shearing device whereby wire may be cut by first passing the latter through the openings 69 and 70 while they are in line with each other, and then rocking the lever 44 relative to the stand. It is also possible to cut strips of metal or the like into various lengths by inserting the same in radial cutting slots 71 and 72 formed respectively on the blade arm 62 of the rock lever 44 and the adjacent part 15 of the stand leg 21, while these cutting slots are in line with each other, and then rocking the lever 44 so that these parts slide by one another in the manner of a pair of shears, thereby severing the respective strip.

25 In order to thus permit of utilizing only the leg 21 of the stand as a part of the shearing or cutting mechanism to the exclusion of the other leg 23 of the stand, the upper part of the leg 23 is cut back, as shown by dotted lines 73 in Fig. 4, so 30 that the same does not interfere with the operation of cutting either a wire or a strip of metal as above described.

For the purpose of enabling the position of a wire rod or strip of metal which is to be cut, 35 bent or perforated to be properly positioned relatively lengthwise to the cutting bending and perforating mechanism, gage means are provided which in their preferred construction include an upright gage arm 14 which is adapted to extend 40 across the path of the wire rod or strip of metal which is to be operated upon, and also capable of being adjusted transversely relative to the stand to suit the length of wire or strip which is required.

45 For this purpose the gage arm 14 is arranged at one end of an adjusting rod 75 which extends transversely through corresponding openings formed in the lower parts of the stand legs 21, 23. By sliding the gage rod 75 lengthwise through the 50 stand legs the gage arm 14 may be shifted lengthwise toward and from the wire and strip cutting, bending and perforating mechanism to suit the length of the articles which is required, and by turning the gage rod 75 in the stand legs the 55 gage arm 14 may be brought into line with either the cutting openings 69 and 70 for severing wire or rods, or into line with the cutting slots 71 and 72 for severing strips of metal or in line with the bending mechanism or in line with the perforating mechanism at the desired place.

After adjustment of the gage arm 14 in the manner described the same is positively held in the required position by clamping means which, as shown in Figs. 1, 3, 4 and 6 preferably consist of a bolt having its inner part arranged in the space between the lower parts of the stand legs and provided with an eye 76 which receives the gage rod 75 while its shank 77 extends laterally beyond the adjacent vertical edges of the 65 stand legs, and a clamping screw nut 78 arranged on the thread of the bolt shank 77 and bears against the outer side of the vertical plate 52 of the punching bracket.

Upon loosening the nut 78 the grip of the eye 75 on the gage rod 75 is released, thereby permit-

ting the latter to be shifted lengthwise and also rotated for bringing the gage arm 14 into the desired position with reference to the wire and strip cutting bending or perforating mechanism, and upon tightening this nut the eye of the bolt will 5 be drawn against the gage rod 75, thereby clamping the same in position on the stand so that the gage arm 14 will be retained in whatever position it has been adjusted.

For the purpose of enabling wires or rods similar to those shown in Figs. 7 and 8 to be provided at their ends with external screw threads 10 19 means are provided on this apparatus for gripping such wires and holding the same in place while a die is engaged either by hand or otherwise 15 with the end of the wire thus held for cutting a screw thread thereon.

In the preferred construction some of the members of the means for gaging the length of the wire or strip which is to be cut, and also members 20 of the punching mechanism are utilized as means for holding the wires or rods while they are being provided with external screw threads. This is preferably accomplished by providing the outer edge of the vertical plate 52 of the punching 25 bracket and the corresponding edges of the stand legs 21 and 23 with V-shaped notches 80, 81, as shown in Figs. 1, 4 and 6, which notches together form a V-shaped seat for engagement with the inner side of a wire or rod while the outer side 30 thereof is engaged by the adjacent inner part of the clamping nuts 78 and thereby securely grip a rod or wire and hold the same reliably in place while a screw threading die is being rotated in engagement with an end of the wire for producing 35 a screw thread thereon.

For convenience in locating the gage arm 14 with reference to the cutting mechanism, the gage rod 75 is provided with a measuring scale 40 of graduations, such as those indicated at 82, which latter may be associated with the adjacent part or surface of the stand in order to conveniently predetermine the location of the gage arm 14 before beginning the operation of cutting the bars or strips of metal into the required lengths. 45

This eye-bolt and its nut therefore serve as part of the means whereby the longitudinal gage for the wire and metal strip are held in place and also as part of the means for holding a wire or rod on the stand while threads are being cut 50 thereon.

As a whole this multiple tool apparatus is comparatively simple in construction, considering the various functions which the same is capable of performing, the same is compact in its organization and it is also strong and durable and not liable to get out of order even though the same is subjected to heavy work. 55

Moreover the several parts of the same are all of simple construction and capable of being made 60 mainly of sheet metal stock, thereby enabling this apparatus to be constructed at comparatively low cost so that the same is well-suited for use in manual training of boys who follow mechanical pursuits. 65

This application is refiled for abandoned application, Serial No. 671,507, filed May 17, 1933.

I claim as my invention:

1. An apparatus of the character described, including a stand composed of two L-shaped sections arranged side by side and each having a horizontal foot and an upright leg which is spaced from the leg of the other section, said legs being provided on one of their corresponding edges with a gripping face, a rod extending hori- 70 75 75

zontally through said legs, a bolt having an eye arranged between said legs and receiving said rod, and a shank extending laterally from said eye, and a clamping screw nut working on said shank 5 and adapted to cooperate with said gripping face for holding an article.

2. An apparatus of the character described including a stand composed of two L-shaped sections arranged side by side and each having a 10 horizontal foot and an upright leg which is spaced from the leg of the other section, said legs being provided on one of their corresponding edges with a gripping face, a bearing piece secured to one of said legs and forming an extension of said gripping face, and a clamping screw nut mounted on said shank and adapted to cooperate with said gripping face and bearing piece for holding an article.

3. An apparatus of the character described, including a stand composed of two L-shaped sections arranged side by side and each having a 15 horizontal foot and an upright leg which is spaced from the leg of the other section, said legs being provided on one of their corresponding edges with a gripping face, a rod extending horizontally through said legs, a bolt having an eye arranged between said legs and receiving said rod, and a shank extending laterally from said eye, and a clamping screw nut working on said shank and 20 adapted to cooperate with said gripping face for holding an article, said rod being longitudinally adjustable on said stand and adapted to be held in place by said eye bolt and nut and provided at one end with a gage arm which is adjustable 25 toward and from said gripping face.

4. An apparatus of the character described, including a stand composed of two L-shaped sections arranged side by side and each having a 30 horizontal foot and an upright leg which is spaced from the leg of the other section, said legs being provided on one of their corresponding edges with a gripping face, a rod extending horizontally through said legs, a bolt having an eye arranged between said legs and receiving said rod, and a shank extending laterally from said eye, and a 35 clamping screw nut working on said shank and adapted to cooperate with said gripping face for holding an article, an L-shaped bracket having a vertical plate secured to one of said legs and a horizontal plate extending over parts of said legs, and a tool mounted on said stand between the 40 legs thereof and adapted to operate on an article supported by said horizontal plate.

5. An apparatus of the character described, including a stand composed of two L-shaped sections arranged side by side and each having a 45 horizontal foot and an upright leg which is spaced from the leg of the other section, said legs being provided on one of their corresponding edges with a gripping face, a rod extending horizontally through said legs, a bolt having an eye arranged between said legs and receiving said 50 rod, and a shank extending laterally from said

eye, and a clamping screw nut working on said shank and adapted to cooperate with said gripping face for holding an article, an L-shaped bracket having a vertical plate secured to one of said legs and a horizontal plate extending over parts of said legs, and a rocking lever pivoted between said legs and provided with a tool adapted to operate on an article supported on said horizontal plate.

6. An apparatus of the character described, including a stand composed of two L-shaped sections arranged side by side and each having a 55 horizontal foot and an upright leg which is spaced from the leg of the other section, said legs being provided on one of their corresponding edges with a gripping face, a rod extending horizontally through said legs, a bolt having an eye arranged between said legs and receiving said rod, and a shank extending laterally from said eye, and a clamping screw nut working on said shank and adapted to cooperate with said gripping face for holding an article, an L-shaped bracket having a vertical plate secured to one of said legs and a horizontal plate extending over parts of said legs, a rocking lever pivoted between 60 said legs and provided with a tool adapted to operate on an article supported on said horizontal plate, and a rocking cam pivoted between said legs and working on said rocking lever and provided with an operating handle.

7. An apparatus of the character described, including a stand composed of two L-shaped sections arranged side by side and each having a 65 horizontal foot and an upright leg which is spaced from the leg of the other section, a tool mounted on said frame and adapted to operate upon an article, a longitudinal rod slidable lengthwise through said legs and provided with a gage arm adapted to be engaged by the article which is to be operated upon, a bolt having a 70 shank and eye arranged between said legs and said eye surrounding the adjacent part of said longitudinal rod, and a screw nut arranged on said shank and engaging with the adjacent edges of said legs.

8. An apparatus of the character described, including a stand composed of two L-shaped sections arranged side by side and each having a 75 horizontal foot and an upright leg which is spaced from the leg of the other section, said stand adapted to receive a plurality of tools arranged upon different parts of said stand and adapted to perform different operations on an article, a longitudinal rod slidable lengthwise through said legs and also capable of rotation 80 therein, a gage arm arranged on said rod and movable lengthwise therewith and also rotatable therewith for bringing said arm into line with one or other of said tools on said stand, and means for holding said rod and arm against 85 movement after the same have been adjusted into the desired position.

HENRY M. YEAGER.
